UNITED STATES PATENT OFFICE

HARRY B. SWAN, OF DETROIT, MICHIGAN, ASSIGNOR TO GENERAL MOTORS CORPORATION, OF DETROIT, MICHIGAN, A CORPORATION OF DELAWARE

MOLDING MACHINE

Application filed November 16, 1929. Serial No. 407,658.

This invention relates to molding machines and has particular reference to a machine which utilizes a rotatable pattern plate or a plate which may be inverted so as to utilize the two complementary patterns on the two sides of the plate.

In the prior art where a split pattern has been used it has been customary to place the pattern in the drag and ram down the sand. A board is then placed over the bottom of the drag and the pattern and drag picked up and turned over. The cope was then placed over the drag and filled with sand and the sand rammed down. The cope is then lifted off the drag and the split pattern removed by hand, after which the cope was replaced to make the mold ready to be poured. This procedure took quite a bit of time and was rather expensive.

In the present invention, a pattern plate is turnably mounted on trunnions in a frame and the two halves of the pattern secured to opposite sides of the plate. The drag is placed on the pattern plate and filled with sand and the sand rammed down. The pattern is then stripped from the mold and the drag is then removed in the usual way such as by applying a vibrator to jar it loose from the pattern. The pattern plate is then rotated or inverted and the cope placed on the opposite side and sand applied and rammed down in the conventional way. The vibrator is again applied to the cope to permit its ready removal, and the cope then placed on the drag and the two are then ready to be poured. This method necessitates less handling and the handling of only cope or drag at one time instead of the entire flask.

If desired (and in practice it is to be preferred) one-half of the pattern plate will first be used to make the series of fifteen or twenty molds (such as the drag) and the plate then inverted and a second series of fifteen or twenty copies prepared to mate with the drags.

The machine of the invention comprises a frame having end uprights and lateral connecting members. Both of the end uprights are provided with a pair of bars adapted to receive a pair of reciprocable bearings in

which are mounted the trunnions of the rotatable pattern plate. The end plates are provided with suitable slots to permit the extension of the trunnions therethrough and to allow for the reciprocation of the bearings. A pair of links attached to the opposite ends of the trunnions is each interconnected with a second link pivotally mounted relative to the frame at one end and provided with operating handles at the other end. By swinging the handles the bearings and pattern plate may be caused to reciprocate. A spring attached to the operating links always tends to hold the pattern plate in its uppermost position and a plurality of pivoted fingers are mounted on the side bars of the frame and are adapted to engage below the plate to retain it in position. Common means is provided to operate the retaining fingers.

At one end of one of the trunnions there is secured a disc which is provided with a pair of recesses into which there is adapted to engage the point of a finger pivoted on one of the bearings. The finger is provided with an extension which is adapted to strike a cam on the frame so that when the pattern plate is moved downwardly, the cam will strike the finger end to cause the point to be released from its recess and permit the rotation of the plate. The finger, when engaged in the recess, will prevent the plate's rotation.

A finger suitably pivoted to the frame, is adapted to be swung on its pivot when the pattern plate is moved downwardly, but on its upward movement the plate will strike the finger to cause the plate to be rotated. The rotation of the plate will of course rotate the disc and after the bearings have been moved to an uppermost position the plate will be at an angle of about 45° and it may be rotated or moved the remainder of its distance by hand.

On the drawings the bearings and their supporting rods are shown as positioned on the outside of the frame for the reason that there is less likelihood of their becoming injured by the sand, although it is within the scope of the invention to place the bearings and rods on the inside of the end pieces.

On the drawings:

Figure 1 is a plan view of the molding machine with parts broken away and shown in section for purposes of clearer illustration.

Figure 2 is a side view of the structure of Figure 1 with one-half the flask in position and parts broken away and shown in section for purposes of clearer illustration.

10 Figures 3 and 4 are end views on the lines 3—3 and 4—4 of Figure 1 with parts broken away and shown in section.

Referring to the drawings, the numeral 2 indicates the molding machine as a whole. 15 The machine has the frame 4 comprising the upright end plates 6 and 8 and connecting side pieces 10 and 12. The end pieces are preferably provided with the top flanges 14 and lateral flanges 16 and are recessed at 20 18 to form the feet 20.

Mounted on the outer sides of the uprights 6 and 8 are the brackets 22 and 24 adapted to receive the lower ends of the rods 26, the opposite or upper ends of which are mounted 25 in bosses 28 formed on the top flanges 14. Mounted on the rods 26 are the bearings 30 which are adapted to slide up and down or reciprocate on the rods 26. The bearings 30 each comprise a pair of cylinders 32 and a 30 connecting piece 34 which has formed thereon the bosses 36 and is provided with an opening for the reception of trunnions 38 rigidly secured as by means of bolts and nuts 40 to a rotatable or turnable pattern plate 42. The 35 end plates 6 and 8 are each provided with a slot 44 to allow the trunnions to extend through the end plates to the bearings 30.

On the end of each trunnion 38, there is 40 pivotally mounted a link 46, both of which extend downwardly and are pivoted as at 48 to rods 50 rigidly connected as at 52 to links or arms 54 pivoted as at 56 to the end uprights 6 and 8 of the frame. A tube 58 is welded to and connects the adjacent pivoted 45 ends of the two links or arms 54 so that the operation of either handle 62 will lower the plate. The arms 54 are each provided with handles 60 which extend laterally of the machine and are provided with the operating 50 ends 62 to be grasped by the operator. The end members 6 and 8 are provided with the arcuate slots 64 to permit the rods 50 to extend therethrough for their operation. By pushing downward on the operating ends 62, 55 the links 54 and rods 50 will pull on the links 46 to pull the bearings 30 and pattern plate 42 downwardly. The purpose of this downward movement will be later explained. The downward pull on the handles 60 and arms 54 60 will tension the springs 63 secured to the free ends of the arms and to a rod or bar 65 mounted between the end uprights 6 and 8. The springs will therefore always tend to return the arms 54 to or hold them in the position shown in Figures 3 and 4 which cor- 65

responds to the normal or uppermost position of the pattern plate 42.

A disc 66, provided with a plurality of recesses 68, is fixed to one end of one of the trunnions 38 and a finger 70 having the point 72 and pivoted as at 74 to a stud 76 rigidly mounted on a bearing 30, is adapted to engage in the recesses 68 to normally hold the pattern plate 42 from rotating. When the point 72 of the finger 70 is engaged in one of the recesses 68, the plate will be prevented from turning. A cam 80 is rigidly mounted on the outside of the end plate 6 immediately below a finger 70 and when the handles 60 are operated to pull the bearings and plate 80 downwardly, the projecting end 82 of the finger 70 will strike the cam surface 84 to cause the finger 70 to swing away from the recess 68 against the tension of the spring 85. When the finger is withdrawn, it will be held 85 by the cam 80 out of the recess until the end 82 is again freed from the cam surface 84.

On the downward movement of the pattern plate 42, the squared portion 86 (Figure 1) of the trunnion mounting 88 will strike 90 against the beveled edge 90 (Figures 1 and 4) of a finger 92 pivoted as at 94 to the end upright 6 at either side of the pattern plate 42. When the squared portion 86 strikes the beveled edge 90, it will swing the finger 92 95 on its pivot and eventually pass the end of the finger to allow it to fall back to the position shown in Figure 4. A lug 96 on the frame 4 will prevent the finger 92 from turning in a counter-clockwise direction beyond 100 the position shown in Figure 4. As the plate now moves upwardly, the upper side of the squared portion 86 will strike the lower or flat side of the tapered end 90 and cause the pattern plate 42 to rotate or turn on its trunnions 38, the finger 70 being still out of the recess 68 owing to the fact that the end 82 is in engagement with the cam 80. The continued upward movement of the bearings 30 and plate 42 will permit the end 82 of the 110 finger 70 to be released from the cam 80 and permit the spring 86 to pull the finger 72 against the periphery of the disc 66. However, inasmuch as the plate has been partially rotated, the groove 68 will not conform to 115 the finger 72 so that the finger will ride on the peripheral edge until the plate has been rotated through 180° to bring the second recess 68 into mesh with the tip 72. The spring 86 will now force the tip into the groove and in this position the plate will be inverted and the side which was uppermost will now face downwardly and the downwardly facing side will be uppermost.

The purpose of this inversion or turning 125 of the plate is to offer or present the two pattern halves for the flask and the cope. The pattern halves are shown diagrammatically at 98, 100, 102 and 104. Considering Figure 1, the operator places the drag over the pat- 130

tern so that it rests on the stripper plate 105 at the frame edge, suitable positioning means being applied on the stripper or pattern plates 42, or both, to properly position the drag. The sand is now placed in the drag and rammed down by hand to get a good shape of mold. After a vibrator has been applied to break the pattern from the sand, the plate 42 may be lowered leaving the drag 5 on the stripper plate 105. The plate may now be reversed or inverted, as has been previously described, and the patterns 102 and 104 brought on the upper side. The cope is now applied and the sand placed therein and rammed down. The vibrator is again applied and the cope withdrawn and placed on top of the drag. The positioning of the cope and drag on the pattern plate is so arranged that when they are taken from the pattern 15 plate and placed on each other, the two mold halves will conform and permit the direct pouring of the metal.

In actual practice, it is preferred to use one side of the pattern plate to form a number of drags and then invert the pattern plate 25 and form a similar number of copies. This is desirable for the reason that it necessitates fewer turnings of the plate and speeds up production.

30 When the plate is in its uppermost position, means is provided to rigidly hold it and prevent its accidental movement. For this purpose there have been provided the fingers 106 at the opposite sides of the machine. 35 The fingers are rigidly mounted on the pivotal rods 108 which extend through the frame sides 12 and have the links 110 secured to the lower ends. The links 110 are in turn pivoted to links 112 connected at their extremities 40 to arms 114 rigidly secured to a rod 116 turnably mounted in brackets 118 secured to the frame upright 8. A handle 120 is secured to the end of the rod 116 and by suitably turning the handle 120 the rod 116 and arms 45 114 are operated to move the links 112 and links 110. The movement of the links 110 will turn the rods 108 to swing the finger 106 which engage beneath the pattern plate 42. Suitable recesses 122 are provided in the 50 sides 10 and 12 to permit the fingers to swing free of the pattern plate 42.

I claim:

1. In a molding machine, a frame, a pattern plate having trunnions, patterns on both 55 sides of said plate, reciprocable bearings for said trunnions mounted on said frame, means for reciprocating said bearings, and means operative on said reciprocation to rotate said plate to present either pattern.
2. In a molding machine, a frame, a pattern plate having trunnions extending outside the frame, patterns on both sides of said plate, reciprocable bearings for said trunnions mounted outside the frame, means for 60 reciprocating said trunnions, and means for

causing the rotation of said plate incident to said reciprocation to present either pattern.

3. In a molding machine, a frame, bars mounted on said frame, bearings mounted on 70 said bars, a pattern plate having trunnions mounted in said bearings, patterns on both sides of said plate, means for moving said bearings on said bars, and means for causing the rotation of said plate incident to the reciprocation of said bearings and plate to 75 present either pattern.

4. In a molding machine, a frame, a pattern plate rotatably and reciprocably mounted in said frame, patterns on both 80 sides of said plate, means for normally holding said plate stationary, means for releasing said holding means, means for reciprocating said plate, and means operative incident to said reciprocation for rotating said plate 85 to present either pattern.

5. In a molding machine, a frame, a pattern plate, patterns on both sides of said plate, trunnions on said plate, bearings for 90 said trunnions, means mounted on one of said bearings and one of said trunnions to normally hold said plate from rotation, means for reciprocating said plate and bearings, means operative incident to said reciprocation for causing the disengagement of 95 said holding means, and means operative incident to said reciprocation for rotating said plate to present either pattern.

6. In a molding machine, a frame, a pattern plate, patterns on both sides of said 100 plate, trunnions on said plate, bearings for said trunnions, means mounted on one of said bearings and one of said trunnions for normally holding said plate from rotation, means for moving said plate and bearings, 105 means for causing the disengagement of said holding means, and means for rotating said plate to present either pattern.

7. In a molding machine, a frame, a pattern plate, patterns on both sides of said 110 plate, trunnions on said plate, bearings receiving said trunnions and reciprocably mounted on said frame, a disc on one of said trunnions having a plurality of recesses, a finger on one of said bearings adapted to engage in said recesses, means for reciprocating the bearings and plate to cause the disengagement of said finger from said recesses, and means for rotating the plate to present either pattern upon the release of said holding means.

8. In a molding machine, a frame, a pattern plate, patterns on both sides of said 115 plate, trunnions on said plate, bearings receiving said trunnions and reciprocably 120 mounted on said frame, a disc on one of said trunnions having a plurality of recesses, a finger on one of said bearings adapted to engage in said recesses, means for reciprocating the bearings and plate, a cam on said frame 125 130

adapted to actuate said finger to remove it from said recesses upon the reciprocation of said plate, and means for rotating the plate upon the release of said holding means to present either pattern.

9. In a molding machine, a frame, a pattern plate, patterns on both sides of said plate, trunnions on said plate, bearings receiving said trunnions and reciprocably mounted on said frame, a disc on one of said trunnions having a plurality of recesses, a finger on one of said bearings adapted to engage in said recesses, means for reciprocating the bearings and plate to cause the simultaneous disengagement of said finger from said recesses, and a finger on said frame adapted to engage said plate when reciprocated to cause said plate to rotate to present either pattern.

10. In a molding machine, a frame, a pattern plate, patterns on both sides of said plate, trunnions on said plate, bearings receiving said trunnions and reciprocably mounted on said frame, a disc on one of said trunnions having a plurality of recesses, a finger on one of said bearings adapted to engage in said recesses, means for reciprocating the bearings and plate, a cam on said frame adapted to actuate said finger to remove it from said recesses upon the reciprocation of said plate, and a finger on said frame adapted to engage said plate when reciprocated to cause said plate to rotate to present either pattern.

11. In a molding machine, a frame, bearings reciprocably mounted in said frame, a rotatable pattern plate mounted in said bearings, patterns on both sides of said plate, links connected to said plate, handles operatively connected to said links and adapted to be moved to reciprocate said plate through said links, resilient means normally holding said plate in its work receiving position, and means for rotating said plate on the movement of said handles to present either pattern.

12. In a molding machine, a frame, bearings reciprocably mounted in said frame, a rotatable pattern plate mounted in said bearings, patterns on both sides of said plate, a linkage having handles for reciprocating said bearings and plate, resilient means constantly urging said linkage in one direction, means for normally holding said plate from rotation but releasable on the reciprocation of said plate, and means for rotating or reversing said plate on its reciprocation to present either pattern.

13. In a molding machine, a frame, a plurality of rods mounted on said frame, a plurality of bearings reciprocably mounted on said rods, a pattern plate turnably mounted in said bearings, patterns on both sides of said plate, a disc rigidly mounted relative to said plate and having a plurality of re-

cesses, means pivoted to one of said bearings and adapted to engage in said recesses to normally hold said plate from rotating, means including handles for reciprocating said bearings and plate, means operative incident to said reciprocation to disengage said pivoted means from said disc to permit rotation of said plate to present either pattern.

14. In a molding machine, a frame, a plurality of rods mounted on said frame, a plurality of bearings reciprocably mounted on said rods, a pattern plate turnably mounted in said bearings, patterns on both sides of said plate, a disc rigidly mounted relative to said plate and having a plurality of recesses, means pivoted to one of said bearings and adapted to engage in said recesses to normally hold said plate from rotating, means including handles for reciprocating said bearings and plate, means operative incident to said reciprocation to disengage said pivoted means from said disc to permit rotation of said plate, and means operative incident to said reciprocation to rotate or reverse said plate to present either pattern.

15. In a molding machine, a frame, a plurality of rods mounted on said frame, a plurality of bearings reciprocably mounted on said rods, a pattern plate turnably mounted in said bearings, patterns on both sides of said plate, a disc rigidly mounted relative to said plate and having a plurality of recesses, means pivoted to one of said bearings and adapted to engage in said recesses to normally hold said plate from rotating, means including handles for reciprocating said bearings and plate, means operative incident to said reciprocation to disengage said pivoted means from said disc to permit rotation of said plate to present either pattern, and a finger pivoted to said frame and operative incident to said reciprocation to cause the rotation or reversal of said plate.

16. In a molding machine, a frame, a plurality of rods mounted on the frame, a plurality of bearings reciprocably mounted on said rods, a pattern plate, patterns on both sides of said plate, trunnions on said plate mounted in said bearings, means on said frame adapted to engage said plate to hold it stationary, means for releasing said holding means, a disc on one of said trunnions having a plurality of recesses, a finger pivoted to one of said bearings and adapted to engage in said recesses to prevent the rotation of said plate, a linkage connected to said trunnions and including operating handles for reciprocating said bearings and plate, means on said frame adapted to be engaged by said finger to remove it from said disc, and a pivoted finger on said frame adapted to engage said plate on its upward movement to cause its rotation to permit either pattern to be presented.

17. In a molding machine, a frame, a pat-

tern plate reciprocably and rotatably mounted in said frame and having patterns on both sides thereof, means for reciprocating said plate, and means operative upon the 5 reciprocation of said plate to cause a rotary movement thereof, said plate capable of rotation to present either pattern.

18. In a molding machine, a frame, a pattern plate mounted in said frame for reciprocable and rotary movement and having patterns on both sides thereof, means operative to cause said pattern plate to take one of said movements, and means operative upon the taking of said one movement to cause said 15 plate to take the other movement, said plate capable of rotation to present either pattern.

In testimony whereof I affix my signature.
HARRY B. SWAN.
